(57) CLAIM

The ornamental design for a tablet case, as shown and described.

DESCRIPTION

FIG. 1. is a perspective view of a tablet case showing the design;

FIG. 2. is a second perspective view thereof;

FIG. 3. is a front elevation view thereof;

FIG. 4. is a rear elevation view thereof;

FIG. 5. is a left side elevation view thereof;

FIG. 6. is a right side elevation view thereof;

FIG. 7. is a top plan view thereof;

FIG. 8. is a bottom plan view thereof; and,

FIG. 9. is a perspective view of the tablet case of FIG. 1, shown in an alternate configuration.

Broken lines seen in the drawings depict portions of the tablet case that form no part of the claimed design.
